US00D586078S

(12) United States Design Patent
Anderson et al.

(10) Patent No.: US D586,078 S
(45) Date of Patent:  Feb. 10, 2009

(54) PASTA

(75) Inventors: Eva Anderson, SanSepolcro (IT);
Giacomo Cestelli, SanSepolcro (IT)

(73) Assignee: Societe des Produits Nestle S.A., Vevey
(CH)

() Term: 14 Years

(21) Appl. No.: 29/298,161

(22) Filed: Nov. 29, 2007

(30) Foreign Application Priority Data

Aug. 30, 2007 (CH) 134202

(51) LOC (9) Cl. 01-01

(52) U.S. Cl. D1/126

(58) Field of Classification Search D1/121,
D1/122, 124, 126, 117, 125, 199; D25/119-135;
426/143, 499, 512, 514, 104, 549, 94, 138,
426/283, 391

See application file for complete search history.
